UNITED STATES PATENT OFFICE

2,525,868

REFRIGERATING SYSTEM HAVING A
DETACHABLE UNIT

Sebastien S. Corhanidis, Athens, Greece

Application November 17, 1948, Serial No. 60,441

10 Claims. (Cl. 62—129)

1

This invention relates to refrigerating systems of the type disclosed in my co-pending application Serial No. 32,480, filed June 11, 1948, now Patent No. 2,489,009, granted November 22, 1949, for Refrigerating System, wherein one or more refrigerator chambers may be maintained within a predetermined range of low temperatures by a single detachable refrigerating unit which is readily adaptable to provide regulated freezing or cooling temperatures in any insulated box or chamber to which it is applied, the refrigerating unit being instantly detachable at will without leaving any opening in the insulation enclosing said chamber. As described in my co-pending application, this refrigerating unit may serve as the sole supply of cooling or freezing means for the refrigerator chambers to which it may be applied, or as an auxiliary for supplying additional cooling means to an overloaded refrigerator chamber, or when additional quick freezing or cooling is desired.

The object of the present invention is to build a compact and complete refrigerating unit and means for adapting it for quick selective application to any one of a number of refrigerator chambers.

A further object is to arrange the parts of the above refrigerating unit so as to form a compact, rugged, but smooth box-like assembly having adjacent inlet and outlet ports in one side, and to provide a frame with matching outlet and inlet ports for installation in a suitable portion of a side wall of a refrigerator chamber, said frame having hanger loops, and complementary hanger hooks on said assembly to hang it instantly over the ports in said frame, so as to form continuous ducts for withdrawing air from said refrigerator chamber and returning it thereto after it had been cooled by the refrigerating unit.

A further object is to provide resiliently operated closure means for the ports in the frame to normally keep the ports closed, a door in the wall of the refrigerating unit, a port in said frame between said ducts with closure means normally resiliently operated to open position, and means responsive to the closing of said door, when said refrigerating unit is hung in place, for operating said first closure means into open position and said second closure means into closed position against the resilient bias, whereby the ducts are open for normal operation whenever the refrigerating unit is applied to the refrigerator chamber and its door is closed; and when its door is opened, as for defrosting, the ambient air admitted through the open door is circulated by the blower of the refrigerating unit through the port between

2

said ducts instead of through the refrigerator chamber, and then through the freezer coils into the atmosphere through the open door for quick defrosting, while the refrigerator chamber is closed off.

A further object is to provide common operating connections for the closure means, which may be in the form of shutters, having a slideable abutment extending axially of said inlet and outlet ports, and an axially slideable rod in said refrigerating unit connected by a hinged link to a pivot on the door and aligned with said abutment for cooperation therewith in the manner prescribed above.

A further object is to provide a modification of the closure means and ports, by having additional closure means for the inlet and outlet ports in the refrigerating unit, and using a port with closure means between the ducts inside the refrigerating unit instead of in the frame, the closure means in the refrigerating unit being connected to the axially slideable rod for operation in a similar way to that in the first mentioned refrigerating system, whereby when the door is opened, the refrigerating unit is quickly defrosted by blowing ambient air through the cooling coils whether the refrigerating unit is hung in place or removed from the refrigerator chamber, and the ports in the frame are closed.

A further object, in both of the above described modifications, is to provide a cut-off switch connected for operation by the axially slideable push rod to shut off the compressor motor and cooling fan in the refrigerating unit whenever the door in the refrigerating unit is opened for defrosting thereof.

Other and more specific objects will become apparent in the following detailed description of some preferred forms of devices built in accordance with the present invention, having reference to the accompanying drawings, wherein:

Fig. 1 is an elevational view of one form of the invention applied to a refrigerator chamber wall, shown partly in section.

Fig. 2 is a similar view of the same form with the door to the refrigerating unit opened for defrosting.

Figs. 3 and 4 are similar views of another form of the invention, showing the door to the refrigerating unit in closed and opened positions respectively.

Fig. 5 is a detail perspective view of a part of the closure means and the operating rod connections to the door shown in Figs. 1 and 2.

Fig. 6 is a similar view of a portion of the

closure means and connections shown in Figs. 3 and 4.

In one form of the device, as illustrated in Figs. 1, 2 and 5, the refrigerating unit comprises a freezing unit enclosed by an insulated wall 1 having a door 2 in one corner thereof, hinged at 3 and having a link 4 pivotally connected thereto as at 5. The other end of the link 4 is pivotally connected to one end of a rod 6 for sliding the rod horizontally in guides 7 mounted in the refrigerating unit when the door is opened and closed.

The lower portion of the refrigerating unit is not insulated but contains the essential motor compressor unit, cooling coils and fan for the refrigerant (not shown), and the motor 8 for the blower 9 driven by a shaft 10 passing through the bottom insulated wall of the refrigerating chamber. The arrangement of parts in the lower portion of the refrigerating unit may be similar to that disclosed in my co-pending application, or any other suitable arrangement.

The side of wall 1 opposite the door 2 has an inlet port 11 at the top and an outlet port 12 below, to match with outlet and inlet ports 13 and 14, respectively, of the frame 15, mounted in a corresponding opening 16 made in the side wall 17 of the refrigerator chamber 18, when the refrigerating unit is hung over said frame by means of hooks 19 on the refrigerating unit slipped into hanger hooks 20 on the frame 15, so that the unit will exert a pressure on the resilient strip 21 which is mounted on the frame 15 around the ports 13 and 14, thus securing an air tight seal for the conduits formed by the matching ports between the refrigerator chamber and the refrigerating unit.

These conduits provide for the passage of the air from the refrigerator chamber 18 through the ports 13 and 11 into the upper portion of the refrigerating unit where the cooling coils 22 are located, through the spaces around these coils and out of the lower portion of the cooling unit through the ports 12 and 14 back into the refrigerator chamber. A partition 24 in the upper cooling unit is partly formed by the drip pan 23 under the cooling coils which drains through tube 25 into an evaporating pan (not shown) in the lower part of the refrigerating unit. The partition 24 has an opening 26 adjacent the open end of the centrifugal blower 9 which draws air from the refrigeration chamber 18 over the cooling coils 22 in the cooling unit for return to said refrigerator chamber 18 after it has been cooled.

It will be observed that the frame 15 is provided with a port 21 connecting the upper and lower ports 13 and 14. This port 21 as well as the internal ends of ports 13 and 14 are provided with shutters 28, 29 and 30, respectively, all interconnected for simultaneous operation by a sliding rod 31 in the guides 32, which are located in line with guides 7 in the cooling unit, when the latter is hung in position on the hanger loops 20. Rod 31 is biased outwardly by spring 33, to normally keep shutters 28 open and shutters 29 and 30 closed. In this position, the outer end of rod 31 just abuts the end of rod 6, when door 2 is open. However, when door 2 is closed, rod 6 moves rod 31 inwardly to a position which closes shutters 28 and opens shutters 29 and 30.

Thus, when the refrigerating unit is applied to the refrigerator chamber and as long as the inspection door 2 is kept closed, a circulation of air is established through the open ports 13

and 14 for providing the desired cooling or refrigeration. Should the inspection door 2 be opened for defrosting or any other purpose, shutters 28 and 30 close off the refrigerator chamber 18, and shutters 28 open to provide a circulation of warm air from the outside entering the open door 2 through the blower, the lower portion of the cooling unit, the port 27, the upper portion of the cooling unit around the cooling coils back through the open door out of the unit, to provide quick defrosting. An electric switch 34 having an operating lever 35 may be connected for operation to the rod 6 so as to be turned on when door 2 is closed, and turned off when the door is opened for the purpose of controlling the operation of the motor compressor and fan.

A manually operated switch (not shown) may be placed in series in the same circuit with switch 34 for manual operation, when the refrigerating unit is removed from the hooks for defrosting. The door 2 in this case is maintained closed so as to provide a continuous passage for the warm air entering port 11, passing around the cooling coils, through the blower and out through the lower portion of the refrigerating unit and port 12.

In the form of the device illustrated in Figs. 3, 4 and 6, the port 27 in frame 15 and shutters 28 are omitted, and the cooling unit is provided with port 27' and shutters 28' in its partition adjacent the ports 11 and 12, and these ports are provided with shutters 29' and 30'. Shutters 23', 29' and 30' are connected to rod 6 for simultaneous operation in accordance with the movement of door 2 into open or closed position. When door 2 is closed, as in normal freezing operation, shutters 28' are closed and shutters 29' and 30' are open, as also are shutters 29 and 30, as shown in Figs. 3 and 6. When door 2 is open, shutters 28' are open and the rest of the shutters are closed, as shown in Fig. 4, for defrosting purposes. In this form, no manual switch for the motor compressor and fan is needed, for defrosting with the refrigerating unit removed from the hanger loops, since ports 11 and 12 are closed by the shutters 29' and 30', and open port 27' is provided to complete the circulation path for the warm air admitted through the open door 2 and blown through and around the cooling coils before being exhausted back to the atmosphere through the open door, in the same way as with the refrigerating unit left in hanging position on the hanger loops 20, since door 2 is left open and keeps the switch 34 in off position for defrosting even when the refrigerating unit is removed from the refrigerator chamber wall.

Figs. 5 and 6 show the construction of the interconnections between the shutters of each group and the operating rods, on an enlarged scale. It will be noticed that the connections to the rods 6 and 31 comprise pins in the rods sliding in slots in pivoted levers to allow the axial sliding movement of the rods while the levers turn angularly about their pivots to operate the shutters.

Many obvious modifications may be made in the details and arrangement of parts of the devices disclosed without departing from the spirit and scope of the present invention, as defined in the appended claims.

What is claimed is:

1. A refrigerating system for refrigerator or cooler chamber, comprising a frame for installation in an opening in the side wall of the refrigerator or cooler chamber, said frame having an

outlet port and a return port for the air in said chamber, a closure means for each of said parts normally held resiliently in their closed position, a refrigerating unit adapted for hanging over said ports and means forming a part of said refrigerating unit and coacting with said closure means for automatically opening said closure means to provide refrigeration or cooling therethrough.

2. A refrigerating system as defined in claim 1, wherein said frame is provided with hanger loops at the top, and said unit is provided with hooks to provide means for hanging said unit over said ports, there being a resilient strip on said frame around said ports to make an air-tight joint by the weight of the unit hanging from the hooks providing a pressure force component thereof normal to the side of said chamber.

3. A refrigerating system as defined in claim 2, wherein said refrigerating unit includes a cooling unit in its upper portion with an insulated wall having inlet and outlet ports matching said outlet and return ports, respectively, of said frame, for withdrawing a stream of air from the chamber to be cooled and returned thereto.

4. A refrigerating system as defined in claim 3, wherein said cooling unit comprises an upper portion separated by a partition from a lower portion, said upper portion connected to its inlet port and said lower portion connected to its outlet port, a freezing or cooling coil in said upper portion adjacent said inlet port, said partition having an opening near its other end connecting said portions, and a centrifugal blower in said lower portion having its open center in registry with said opening and discharging into said lower portion, to provide the desired circulation of the air through the cooling unit and cooling of the air as it passes around the cooling coils.

5. A refrigerating system as defined in claim 4, wherein said blower is operated by a shaft passing through said insulated wall from a motor mounted in said refrigerating unit below said wall.

6. A refrigerating system as defined in claim 5, a door in the upper portion of said cooling unit adjacent said opening, and a slideable control rod connected for operation by opening said door to release said closure means into normal closed position to close off said chamber from the outside atmosphere entering said open door.

7. A refrigerator system as defined in claim 6, said closure means being at the inner ends of said outlet and return ports, a port in said frame between said outlet and return ports and closure means therefor having connections for operating

it simultaneously with the other closure means so as to normally keep it open when the others are closed and vice versa, whereby to furnish a by-pass for the circulation of warm air from the lower portion of the cooling unit to the upper portion and around said cooling coils out through said open door for quick defrosting when said door is opened, and for causing circulation for cooling of the air from the chamber through said cooling unit when said door is closed.

8. A refrigerating system as defined in claim 7, and a switch connected for operation by said control rod to cut off the motor compressor and fan for cooling the refrigerant normally used during refrigeration, when said door is open.

9. A refrigerating system as defined in claim 6, a closure means in said inlet and outlet ports of said cooling unit, a port in said partition between said upper and lower portions of said freezing unit adjacent said closures, said last named port having closure means, all said closure means in said cooling unit having connections to said control rod for simultaneous operation so as to close said closure means in said last named port and open said other closures in said cooling unit when said door is closed to complete the circulating passage through said cooling unit when the door is closed for cooling the air taken from said chamber, and to by-pass the warm air taken in from the atmosphere from said lower portion to the upper portion for quick defrosting when said door is open regardless of whether the refrigerating unit is hung in place over said frame or removed therefrom, while the inlet and outlet ports are closed off by their respective closure means and the chamber is closed off by the closure means in the outlet and return ports in said frame.

10. A refrigerating system as defined in claim 9, a motor compressor and fan for compressing and cooling the refrigerant mounted in the lower part of said refrigerating unit, and a switch in said cooling unit connected for operation by said control rod to cut off said motor compressor and fan when said door is open.

SEBASTIEN S. CORHANIDIS.
